COMBINED FOODSTUFF SLICER GUIDE AND SLICING KNIFE

Maria Benktzon, Sollentuna, and Sven-Eric Juhlin,
Gustavsberg, Sweden, assignors to AB Gustavsberg
Fabriker, Gustavsberg, Sweden

Filed Oct. 25, 1973, Ser. No. 409,735

Claims priority, application Sweden May 2, 1973

Term of patent 14 years

Int. Cl. D7—04

U.S. Cl. D7—43

FIG. 1

FIG. 2

FIG. 3

FIG. 4

FIG. 5

FIG. 1 is a top perspective view of a combined foodstuff slicer guide and slicing knife showing our new design;

FIG. 2 is a perspective top view of the stand of the slicer guide;

FIG. 3 is a bottom perspective view of the stand of the slicer guide;

FIG. 4 is a perspective view of the support member of the slicer guide; and

FIG. 5 is a perspective view of the slicing knife thereof showing the side opposite of that shown in FIG. 1.

We claim:

The ornamental design for a combined foodstuff slicer guide and slicing knife, as shown.
